UNITED STATES PATENT OFFICE.

JOSEPH E. HULL, OF RODAMERS, WEST VIRGINIA.

SACK-HOLDER.

939,508.

Specification of Letters Patent. Patented Nov. 9, 1909.

Application filed April 10, 1909. Serial No. 489,135.

To all whom it may concern:

Be it known that I, JOSEPH E. HULL, a citizen of the United States, residing at Rodamers, in the county of Preston and State of West Virginia, have invented certain new and useful Improvements in Sack-Holders, of which the following is a specification, reference being had to the accompanying drawings.

10 This invention relates to improvements in devices for holding sacks, bags, and the like while they are being filled with grain or other material.

The object of the invention is to provide 15 a simple and practical device of this character which may be applied to a wall or any other upright support and the parts of which may be quickly and easily adjusted to support different sized bags.

20 With the above and other objects in view, the invention consists of the novel features of construction and the combination and arrangement of parts hereinafter fully described and claimed, and illustrated in the 25 accompanying drawings, in which—

Figure 1 is a perspective view of the invention showing a sack or bag suspended therefrom; Fig. 2 is a detail vertical section through the device; and Fig. 3 is a detail 30 horizontal section taken on the plane indicated by the line 3—3 in Fig. 2.

The invention comprises an upright 1 preferably made a part of a U-shaped bracket 2, the parallel arms of which have outturned 35 apertured ends 3 which may be secured to a wall or other vertical support by screws or similar fastenings. The upright portion 1 of the supporting bracket is formed with a longitudinal series of seats 4 preferably in 40 the form of openings cut in a centrally arranged, longitudinally extending rib 5 which is pressed out of the upright portion 1 of the bracket for the purpose of reinforcing said portion.

45 The sack or bag S which is to be supported is arranged upon a member 6 slidably and adjustably mounted on the upright 1. Said member 6 is in the form of a slide having suitable bag engaging means and a catch 50 or dog to engage the seats 4 and thereby retain the member or slide in an adjusted position. As illustrated, said member or slide 6 is formed from a single piece or strap of metal by bending the same upon itself at its 55 center to provide a rearwardly extending arm 7, then bending its intermediate por-

tions outwardly in opposite directions to provide opposing loop portions 8 to slidably engage the opposite edges of the upright 1, and then bending the extremities or ends 60 of said metal strap to provide opposing curved or arc-shaped sack distending arms 9. Owing to the resiliency of the metal strap, the arms 9 may be sprung together to permit them to enter the open top or mouth of the 65 sack, thereby enabling the use of sacks having different diameters on the device, and said spring arms 9 are provided upon their outer faces with hook-shaped spurs 10 or equivalent means for engaging the sack and 70 retaining it upon the arms. In the bottom edges of the inner portions of said arms are formed notches 11 in which the edge of the sack may be arranged, as shown in Fig. 1. The loop portions 8 are retained in engagement with the upright 1 by means of a rivet, bolt or similar transverse fastening 12 passed through the spaced side portions of the rear arm 7 and said part 12 serves the further purpose of a pivot for the catch or 75 dog 13. The latter is disposed in the rear arm 7 and hung at a point intermediate its ends from the pivot 12, its forward end being shaped to provide a dog proper 14 which swings into and out of engagement with one 80 of the seats or openings 4 in the upright 1. The other or rear end of said catch is made of sufficient size and weight to overbalance the end 14 and to provide both a stop and a hand piece. As illustrated, said rear end has 85 a depending portion 15, the extremity of which extends upwardly and out of the top of the arm 7 and it is bent rearwardly to provide a finger piece 16 which rests upon the upper end of the arm 7 when the dog 90 95 or end 14 enters one of the seats 4. It will be seen that when the finger piece 16 is lifted the dog 14 will be swung rearwardly out of engagement with the upright 1 and that when said finger piece is released the catch 100 will drop to its locked position shown in Fig. 2. While said catch 13 is shown in the drawings as made from a single piece of wire, it will be understood that it may be otherwise constructed. The use of the invention will be readily understood upon reference to Fig. 1. It will be noted that the bracket may be attached to a wall or any upright support and that the bag carrying slide or member 6 may be quickly and easily 105 110 adjusted vertically upon it to accommodate bags of different lengths and further that

the resiliency of the jaws 9 permit the application of bags of different widths or diameters to the device.

Having thus described the invention what is claimed is:

- 5 1. A device of the character described comprising a U-shaped bracket having its parallel arms disposed horizontally and formed at their extremities with apertured attaching feet, the intermediate portion of said bracket being disposed vertically and having a longitudinal series of seats, a horizontally disposed bag supporting member arranged for sliding movement on said vertically disposed connecting portion of the bracket and a catch upon said bag supporting member and adapted to engage said seats.
- 10 2. A device of the character described comprising a bracket for attachment to an up-

right support and provided with an upright portion having a longitudinal series of seats, a horizontally disposed, vertically adjustable member consisting of oppositely disposed intermediate loops to slidably engage the opposite edges of said upright portion of the bracket, a rearwardly extending open arm, and forwardly extending oppositely curved arms, means upon the latter for engaging and supporting a sack, and a pivoted catch in the open portion of the rear arm and adapted to engage said seats in the upright portion of the bracket.

In testimony whereof I hereunto affix my signature in the presence of two witnesses.

JOSEPH E. HULL.
